DESIGN FOR A PRINTED FABRIC

William A. Basser, New York, N. Y.

Application October 26, 1936, Serial No. 65,507

Term of patent 3½ years

To all whom it may concern:

Be it known that I, William A. Basser, a citizen of the United States, residing at New York, in the county and State of New York, have invented a new, original, and ornamental Design for a Printed Fabric of which the following is the specification, reference being had to the accompanying drawing, forming a part thereof.

The figure is a plan view of a printed fabric showing my new design, the lines on the drawing encompassing a repeat motif thereof.

I claim:

The ornamental design for a printed fabric as shown and described.

WILLIAM A. BASSER.
